UNITED STATES PATENT OFFICE.

SAMUEL YATES, OF MUSCOGEE, INDIAN TERRITORY.

CLAMP FOR SOLDERING EAVES-TROUGHS.

SPECIFICATION forming part of Letters Patent No. 326,372, dated September 15, 1885.

Application filed July 20, 1885. (No model.)

To all whom it may concern:

Be it known that I, SAMUEL YATES, a citizen of the United States, residing at Muscogee, in the Creek Nation, Indian Territory, have 5 invented certain new and useful Improvements in Machines for Manufacturing Eaves-Troughs; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to machines for manufacturing eaves-troughs and gutters; and it consists in a certain improvement on a device for such purpose for which Letters Patent No. 57,615 were issued to me August 28, 20 1866.

In the accompanying drawings, Figure 1 is a perspective view of my improved device. Fig. 2 is an end view of the same. Fig. 3 represents a plan view of the same inverted.

25 A designates a semi cylindrical bar, commonly made of wood, to which the metal sheets of which the eaves-trough is to be constructed are secured for soldering. The bar has a pivotal support at both ends in posts B, being 30 pivoted in such a manner that the bar, with its attachments, is balanced with its convex surface upward.

C indicates a plate fastened to the lower surface of bar A at its edge, and to said 35 plate are severally hinged the clamping-bands D, conforming, as shown, to the convex surface of the bar, and having formed at their hinged ends small curves or offsets e, to close about a bead on the edge of the trough. A number of the bands D are placed a suitable distance apart, so as to close over the bar A, where the edges of the sheets lap one on another to be soldered together, and, as shown in Fig. 3, each of the bands is laterally adjustable at its hinged end to the right or left, having a limited movement on a rod. b.

In the bar A or plate C, or both, are formed recesses E, which permit the hinged ends of the clamps D to move along the rods b. The object of this is to enable the workman to set 50 the clamping-band at either side of the soldering line, according to the direction in which it is intended the water shall run in the trough, the metal sheetslapping one on another, so that the water passes freely over the seams. 55

To the underside of bar A, or to plate C, are secured a number of springs, d, each spring being in position to connect with one of the bands D, and thus form a clamp. Each of said springs is formed of a substantial rod, and 60 has one end secured by a pivotal connection to plate C, the other end being extended forward to lock with a band D. The spring is firm in its position when locked with the band, which is held down firmly on the metal sheets 65 placed on the bar, but when unlocked it may be turned to the right or left, according to the relative position of the band, to which it may be locked by pressing its free end into one of the notches e in opposite edges of the band. 70

In Fig. 3 the change of position of a band D and the movement of spring-rod d are indicated in dotted lines at x.

The improvement described is found in practice to add considerably to the utility and 75 convenience of the device.

Having described my invention, I claim—

In a clamping device for the manufacture of eaves-troughs, in combination with a semi-cylindrical bar, A, laterally-movable hinged 80 bands D and pivoted spring-rods d, adjustable to the right or to the left to connect with said bands, substantially as set forth and described.

In testimony whereof I affix my signature 85 in presence of two witnesses.

SAMUEL YATES.

Witnesses.

P. U. BLACKSTONE,
J. H. McQUARIE.
